COMBINED FIREPLACE SCREEN AND PLANTER OR SIMILAR ARTICLE

Loweda H. Love, Oak Ridge, Tenn.

Application March 28, 1955, Serial No. 35,235

Term of patent 14 years

(Cl. D81—5)

FIG. 1

FIG. 3

Fig. 1 is a front view of a combined fireplace screen and planter or similar article showing my new design.

Fig. 2 is a top plan view thereof.

Fig. 3 is a side elevational view thereof. The other side not shown is the same.

I claim:

The ornamental design for a combined fireplace screen and planter or similar article, as shown and described.
